TELEPHONE SYSTEM

William J. Vincent, Rochester, N. Y., assignor to
Rochester Telephone Corporation, Rochester,
N. Y., a corporation of New York

Application May 28, 1936, Serial No. 82,284

2 Claims. (Cl. 179—84)

This invention relates to telephone systems and more particularly to sub-station signalling or ringing arrangements for use therein.

In harmonic ringing systems, the number of 5 telephone bells that can be signalled selectively on a party telephone line without a ground connection at each sub-station, is limited to the number of ringing current frequencies available. Four such frequencies are commonly employed in 10 telephone practice but on occasion five such frequencies are used. For urban subscribers the use of four sub-stations on a party line affords satisfactory service but in rural districts where the subscribers are farther apart, more sub-stations 15 are connected to such a line for economic reasons.

In order to obtain selective ringing on party lines having more sub-stations than the available 20 number of ringing frequencies, it is customary to provide pairs of sub-station ringers tuned to the same ringing frequency, the ringers of a pair being respectively connected between opposite 25 sides of the telephone line and ground. Such an arrangement is commonly referred to as divided sub-station signalling. In an arrangement of this kind, eight sub-stations on a telephone 30 line can be selectively signalled by the use of four ringing frequencies and ten sub-stations on a line can be selectively signalled when five ringing frequencies are employed.

In addition to employing the above described 35 harmonic ringing there has been widely used, a ringing arrangement in which alternating ringing current is superimposed on direct current, in effect providing a pulsating current. In such an arrangement two of the sub-stations of a four party telephone line are bridged between 40 one side of the line and ground while the two other sub-stations are similarly connected between the other side of the line and ground. The ringers of these sub-stations are properly 45 biased so that a pair thereof respectively connected to the opposite sides of the line and ground, respond to positive pulsating current and the other pair of sub-stations respectively connected to the opposite sides of the line respond to negative pulsating current. This arrangement is also referred to as divided ringing.

Both of the arrangements above described afford 50 satisfactory station signalling when the telephone lines are not exposed to foreign currents from power lines since the inductive disturbance caused by the connection of the ringers to ground will not be objectionable especially if an equal 55 number of sub-stations are connected to each

side of the line. However, an equal number of 5 bells cannot always be connected to each side of the line because of the removal of a sub-station on the line due to the subscriber's discontinuance of service. If the telephone line is thus unbalanced, the noise level on the line may rise to a point where it will interfere with satisfactory telephone transmission. But even if the telephone line is balanced by having an equal 10 number of ringers or bells connected to its respective sides, inductive disturbances from power wires paralleling the telephone line for even a short distance, will seriously affect the telephone transmission so that operating companies have resorted to some arrangement for disconnecting 15 the substation bells or ringers, from ground at all times except when ringing current is applied to the line. Such a result is accomplished by providing a special relay at each sub-station which is actuated by ringing current to close the circuit of the bell to ground only while ringing 20 current is applied to the telephone line. These relays are bridged across the telephone line and operate in response to all frequencies, although they operate more dependably on the lower frequencies. While the impedance of these relays 25 is rather high in order to have as little effect as possible on telephone transmission, there is a slight transmission loss resulting therefrom and when automatic ringing is used, there is a noticeable increase in the tendency for premature 30 "tripping" of the ringing current. Furthermore, such relays are expensive and since their contacts must be adjusted to have a light contact pressure, the cost of maintaining them in such 35 adjustment is also an appreciable factor. Furthermore, such a relay has inertia due to its moving parts so that there is an appreciable time lag between the application of the ringing impulse and the operation of the ringer.

The main feature of the present invention relates to the provision of a ringing arrangement whereby a ringer at a substation on a telephone line is electrically connected to ground, by a device without moving parts, only during the time 45 that ringing current is being applied to the telephone line.

Another feature of the invention relates to a ringing arrangement in which the ringer of a telephone line is connected to ground in a circuit 50 including a gaseous section which offers infinite resistance to the passage of current therethrough until the difference in potential closes the terminals of the gaseous section rises to approximately fifty volts after which the resistance 55

thereof decreases as the voltage across the same increases.

A further feature of the invention relates to the use of an arc discharge device for temporarily connecting the ringer of a sub-station to ground during the time when ringing current is applied to the telephone line.

Other features of the invention will appear from the detailed description and claims when taken with the drawing in which Fig. 1 is a dia-
10 grammatic showing of a portion of a telephone system of which only a calling telephone line, a called multiparty telephone line and a link circuit for interconnecting these lines are illus-
15 trated; Fig. 2 is a longitudinal section through, and Fig. 3 is an end view of a rare gas device or discharge tube suitable for use at a sub-
station of the system of the present invention, and Fig. 4 is a chart showing the operating char-
20 acteristics of this device.

At the left hand portion of Fig. 1 there is illustrated a single party telephone line L having connected thereto a substation A of the usual "booster" type. This line is connectible to a link circuit LK by any suitable manual or mechanical switching means the specific switching means being omitted, as indicated by the broken line connection. It will be understood that this link circuit can be a conventional cord circuit or it
25 can be a connecting circuit of a call distributing system. A satisfactory type of cord circuit for use in the system, is illustrated in the patent to Slough 1,519,271 granted December 16, 1924 wherein harmonic ringing is provided, but a link circuit such as disclosed in the patent to Martin 1,541,368 granted June 9, 1925 may also be employed where biased ringers at the substation in a party line are to be actuated by pulsating ringing current.

40 A called telephone line L2 having four sub-
stations or parties thereon is illustrated of which only the substation B having a ringer R1 is illustrated in detail. It will be noted that the ringer R1 as well as the ringers R2, R3 and R4 of the remaining substations on the line are each connected from one side of the line to ground through an arc discharge device or a rare gas tube 10 to be described. Similarly, the ringers R5, R6, R7 and R8 are likewise connected between the other side of line and ground through an arc discharge device or gaseous tube 10. The ringers R1 and R5 may be tuned to respond to ringing current of 16 $\frac{2}{3}$ cycles frequency, ringers R2 and R6 are responsive to ringing current of 33 $\frac{1}{3}$ cycles, ringers R3 and R7 are responsive to ringing current of 50 cycles and ringers R4 and R8 are responsive to ringing current of 66 $\frac{2}{3}$ cycles. It should be understood however, that these ringers may be of the biased type to respond to pulsating ringing current as is more fully disclosed in the mentioned patent to Martin.

45 The arc discharge device or rare gas tube 10 for use at certain of the substations, may be of the general construction illustrated in Figs. 2 and 3, Fig. 2 being a longitudinal section through the tube and Fig. 3 an end view thereof. The device comprises a sealed tube preferably of glass having electrodes 11 and 12 sealed into the respective ends of the tube and projecting into the interior thereof in the relation shown in Fig.
50 2. Certain connection terminals 13 and 14 are attached respectively to the electrodes 11 and 12. The tube, before it is sealed, is preferably filled with a rare gas medium such as neon, argon or a mixture of these gases. The construction of
55

the tube and the composition of the gaseous medium therein are more fully disclosed in an application of F. R. Balcar, about to be filed by the Air Reduction Co. This tube is so designed that it has a characteristic curve C as illus-
5 trated in Fig. 4, that is, the tube offers substan-
10 tially infinite resistance to the passage of current therethrough until the difference in potential across its terminals 13 and 14 rises to around fifty volts, at which time the gas in the gap be-
15 tween the electrodes breaks down and current starts to flow therebetween. As this voltage increases the resistance of the gas decreases with the result that more current flows through the tube. Since the normal voltages existing across the telephone line during conversation is always less than fifty volts, the ringers have no effect on the telephone transmission over the line.

20 In the establishing of a telephone call from the substation A on the telephone line L, to the sub-
station B on the called telephone line L2, the subscriber removes his receiver 16 from its switch hook 17 to initiate the call. If the system is a manual telephone system, the initiation of the call, signals a telephone operator who connects 25 one end of the link LK to the line. If the system is a call distributing system, an automatic switch connects the link LK to the terminals of the line. The method of connecting the line L to the link has not been illustrated since it forms no part 30 of the invention and is well known in the art. After the connection of the link LK to the line L, the operator depresses the listening key 18 to connect her telephone set (not shown) to the line. On receiving the number and party designation of the called subscriber's substation, the operator inserts the plug 19 into the jack 20 of the called line 22. The insertion of the plug 19 into the jack 20 completes a circuit for energizing the cutoff relay 21 of the called line, the 40 circuit being completed through the sleeve contacts of the jack 20 and plug 19 and through the sleeve relay 21 of the link circuit to ground. The cutoff relay is thus energized and its armatures and back contacts disconnect the line re-
45 lay 23 from its line. After this connection of the link to the called line L2, the operator closes ringing key contacts 24 and 25 in the ringing circuit to connect ringing current of the proper frequency to signal the called subscriber's sub-
50 station B.

55 The closure of the upper contacts 25, on the actuation of the ringing key, shunts the ringers R5, R6, R7 and R8 to ground over the lower side of the line, tip contacts of the jack 20 and plug 19, conductor 26, upper contacts 25, conductor 27 to the ground connection. However, ringing current of 16 $\frac{2}{3}$ cycles frequency is applied from this frequency source, over conductor 28, contacts 24 now closed, through the normally 60 closed contacts 29, 30 and 31 of the other ringing frequency selection keys, the lower contacts 25, ring contacts of the plug 19 and the jack 20 over the upper side of the line and through all of the ringers R1, R2, R3 and R4 to ground through 65 their respective discharge tubes 10. This ringing current which is at least eighty volts or over, is effective to break down or ionize the gas in the gap between the electrodes 11 and 12 of the tubes associated with the last-mentioned ringers so 70 that the ringing current temporarily passes through all of these ringers but only the ringer R1 which is tuned to 16 $\frac{2}{3}$ cycles frequency is actuated. In the event that automatic ringing is employed the removal of the called subscriber's 75

receiver 32 from its switch-hook is effective to trip the ringing by a well-known arrangement now shown.

In the present system two connection jacks 20 and 33 are connected to the called line L2. It will be noted that the connections between the tip and ring contacts of these jacks and this line are reversed, that is while the upper and lower sides of the line are respectively connected to the tip and ring contacts of the jack 33, the lower and the upper sides of this line are respectively connected to the tip and ring contacts of the jack 20. In this arrangement the jack 20 may have one numerical designation such as No. 2345 and the jack 33 may have the numerical designation 2346 so that substations having ringers responsive to the same frequency have a different number. In this way the operator's routine will be the same whether she is establishing a connection to a four party line or to an eight party line and obviates the need of a reversing key in the link circuit.

When any of the substations whose ringers R5, R6, R7 and R8 are connected to the ring or lower side of the line are to be signalled, the plug 19 is inserted into the jack 33 and the desired substation ringer is actuated in the manner described above.

From the foregoing it will be seen that the rare gas tube or arc discharge device 10 affords a simple inexpensive means without moving parts, for temporarily connecting the ringer of a called substation to ground during the interval that ringing is applied to the called line. While selective ringing has been disclosed, it will be obvious that code ringing may also be employed in connection with the present invention.

What I claim is:

1. In a telephone system, a telephone line having a plurality of substations connected thereto, a ringer at each substation, each of certain of said ringers being connected between one side of the line and ground through a gaseous tube and through a condenser in series therewith, each of the remainder of said ringers being connected between the other side of the line and ground through a gaseous tube and through a condenser in series therewith, a link circuit connectible to said telephone line, a plurality of sources of ringing current of different characteristics equal in number to the maximum number of ringers connected to one side of said line, and means including said link circuit for connecting a selected source of ringing current to either of said sides of the line. 5 10 15

2. In a telephone system, a telephone line having a plurality of substations connected thereto, a ringer at each substation, each of certain of said ringers being connected between one side of the line and ground through a gaseous tube, each of the remainder of said ringers being connected between the other side of the line and ground through a gaseous tube, each of the ringers connected to one side of the line being tuned to respond to a different ringing current frequency, a link circuit connectible to said telephone line, a plurality of sources of ringing current of different frequencies, the number of such current sources being equal to the number of ringers connected to one side of said line, and means including said link circuit for connecting a selected source of ringing current to either of said sides 20 25 30 35 of the line.

WILLIAM J. VINCENT.
